(57) CLAIM

The ornamental design for a umbrella and support attachment combination, as shown and described.

DESCRIPTION

FIG. 1 is a front elevated view of an umbrella and support attachment combination showing my new design;

FIG. 2 is a left side elevated view of the umbrella and support attachment combination;

FIG. 3 is a right side elevated view of the umbrella and support attachment combination;

FIG. 4 is a top plan view of the umbrella and support attachment combination; and,

FIG. 5 is a bottom plan view of the umbrella and support attachment combination.

The writing in FIG. 1 in broken lines is for illustrated purposes only and forms no part of the claimed invention.
